Primary Examiner—Louis S. Zarfas*Assistant Examiner*—Eric Watterson*Attorney, Agent, or Firm*—Thomason & Moser[57] **CLAIM**

The ornamental design for an aperture for a gutter cover, as shown and described.

DESCRIPTION

FIG. 1 is a frontal elevation view of an aperture for a gutter cover showing my new design;

FIG. 2 is a perspective view of a portion of a gutter cover incorporating the aperture of the invention within two rows of apertures;

FIG. 3 is a perspective view of a portion of a gutter cover incorporating the aperture of the invention within a single row of apertures; and,

FIG. 4 is a cross-sectional side view of an aperture for a gutter cover of the present design taken along line 4—4 of FIG. 2.
